(57) CLAIM

The ornamental design for the spectacles, as shown and described.

DESCRIPTION

FIG. 1 is a perspective view of the spectacles of the present invention;

FIG. 2 is a front view of the spectacles of FIG. 1;

FIG. 3 is a rear view of the spectacles of FIG. 1;

FIG. 4 is a right side view of the spectacles of FIG. 1;

FIG. 5 is a left side view of the spectacles of FIG. 1;

FIG. 6 is a top plan view of the spectacles of FIG. 1;

FIG. 7 is a bottom plan view of the spectacles of FIG. 1;

FIG. 8 is a front left side perspective view of the spectacles of FIG. 1; and,

FIG. 9 is a greatly enlarged, partial perspective view of the left side of the spectacles of FIG. 1.

The broken lines in the FIG. 9 view depict the boundaries at which the partial view is cut off, and form no part of the claimed design.

1 Claim, 7 Drawing Sheets
